INVENTOR.

JAMES. GEDDES.

By *Edgar Phane*
Attorney

UNITED STATES PATENT OFFICE.

JAMES GEDDES, OF WALNUT PARK, CALIFORNIA, ASSIGNOR TO HATTIE R. GEDDES.

CONVEYER.

Application filed August 7, 1924. Serial No. 730,629.

My invention relates primarily to a conveyer for moving loads for short distances, such as loads of lumber into and out of the yard, or into and out of a mill; and the object thereof is to provide cheap and efficient mechanism that can be operated with a minimum consumption of power and will produce the maximum of efficiency.

In the drawings forming a part of this application:

Figure 1 is a plan view of my conveyer.

Fig. 2 is an enlarged fragment in side elevation of a portion of the conveyer.

Fig. 3 is an enlarged sectional detail of a part of the conveyer.

Referring to the drawings, my conveyer consists of two or more pairs of parallel rails, each pair comprising rails A and B. These rails may extend the whole distance that the load is to be transported or they may be made in sections, but each section would be operated in the same manner as if the rails were each a single length.

At suitable distances along and supporting the rails, are pairs of wheels C and D rigidly mounted respectively on the axles E and F, revolvably mounted in bearings H on sills I, which axles are driven at a suitable rate of speed by any suitable gearing, such as a worm gear J on each shaft E meshing with a worm on shaft K and intermeshing gears L on shafts E and F, power being applied to drive shaft K.

Wheels C are the driving wheels and are composed of the offset sections C¹ and C² which have a common hub C³. Each section comprises one-half the periphery of the wheel and is flanged.

Wheels D are the return wheels and are composed of two offset sections D¹ and D², which have a common hub D³. Each section has a flanged circular periphery and is a little less than a half circle and the length of the periphery of each section is the same as that of each section of wheels C plus the vertical distance that the rails A and B travel while being raised or lowered as hereafter explained. Wheels D are a little lower than wheels C and the periphery of the sections are a little further from shaft F than the periphery of wheels C are from shaft E.

With the rails in the position shown in Fig. 2 the load G is supported by rails A and rails A are supported and moved in the

direction of the arrow by flanged section C¹, and rails B are supported and moved in the direction of the arrow by flanged section D². Power being applied to cause the rotation of axles E and F, it will be seen that section C¹ can cause rail A to travel a distance equal to the length of the periphery of the section engaging rail A and that section C² is engaging rail B and lifting it up under load G and that rails A and B will then travel together in the direction of the arrow on rail A or forward, and that section C¹ will cease to support rail A which will then drop upon section D¹ and will be moved in the direction of arrow on rail B or toward the rear. As the points of load support of the peripheries of wheels C and D are directly over shafts E and F, it only requires the minimum amount of power to revolve the shafts, and the maximum load for the amount of power consumed is moved forward. By reversing the revolution of the shafts, the load can be moved backwards. The movement of the rails toward the rear is so timed that when their rearmost travel is reached, they are ready to be engaged and lifted up and then carried forward by the driving wheels.

By this construction, the load is moved forward in the same plane and no power is lost in raising and lowering the load as shown in U. S. Patent No. 666,865. Wheels C and D may be called mutilated wheels.

Having described my invention, I claim:

1. A conveyer comprising a plurality of parallel rails, means to support and move said rails comprising driving wheels and return wheels, said wheels being mutilated wheels, the driving wheels being adapted to alternately move the rails to a supporting and load carrying position and to move them either forward or backward as desired, the return wheels being adapted to alternately move said rails backward or forward as desired; and means to cause the rotation of said wheels.

2. A conveyer comprising a plurality of pairs of parallel rails; axles extending transversely to said rails and beneath the same; a portion E of said axles having rigidly mounted thereon driving wheels, each wheel comprising a hub having mounted on the sides thereof offset sections, one offset section being adapted to support and move one of a pair of rails for one-half the revolution

of the wheel, and the other offset section being adapted to support and move the other of a pair of rails for the other half of the revolution of the wheel, the other portion F 5 of said axles having rigidly mounted thereon return wheels, each wheel comprising a hub having mounted on the sides thereof offset sections, the section on one side being adapted to return one of a pair of rails to 10 the rear and the other section to return the

other rail of the pair to the rear; and means to revolve said axles.

3. In a device of the character described load moving wheels having the periphery thereof composed of offset sections, each section being the one half of a circle. 15

In witness that I claim the foregoing I have hereunto subscribed my name this 1st day of August, 1924.

JAMES GEDDES.
